CLAIM

The ornamental design for a bottle, as shown and described.

DESCRIPTION

FIG. 1 is a perspective view of the bottle of our design; FIG. 2 is a front elevation view thereof, the rear elevation view being a mirror image thereof.

FIG. 3 is a left side elevation view thereof.

FIG. 4 is a right side elevation view thereof.

FIG. 5 is a top plan view thereof.

FIG. 6 is a bottom plan view thereof.

FIG. 7 is a perspective view of a first alternate embodiment of the bottle of FIG. 1.

FIG. 8 is a front elevation view thereof, the rear elevation view being a mirror image thereof.

FIG. 9 is a left side elevation view thereof.

FIG. 10 is a right side elevation view thereof.

FIG. 11 is a top plan view thereof.

FIG. 12 is a bottom plan view thereof.

The broken line showing is for illustrative purposes only and forms no part of the claimed design.
